UNITED STATES PATENT OFFICE.

THEODOR BERG, OF WERDOHL, GERMANY.

TUYÈRE FOR BLAST PIPES FOR HIGH AND OTHER METALLURGICAL FURNACES.

Application filed April 9, 1924. Serial No. 705,396.

To all whom it may concern:

Be it known that I, THEODOR BERG, a citizen of the Republic of Germany, residing at Werdohl, in Westphalia, Germany, have **5** invented certain new and useful Improvements in Tuyères for Blast Pipes for High and Other Metallurgical Furnaces, of which the following is a specification.

The invention relates to improvements in **10** tuyères for blast-pipes for the use in metallurgical furnaces and the same is particularly applicable to the blast-pipes of high furnaces and its object is on the one hand to provide a tuyère which is capable of **15** withstanding the chemical and thermal influences and of resisting the corrosive action of the contents of the furnace, and on the other hand the invention makes it possible to obtain the tuyère in a cheap and simple **20** manner by means of casting the same in a way that the tuyère contains the chamber necessary for the passage of the cooling-water.

The invention is characterized by the **25** feature that the body of the tuyère containing the chamber for the cooling-water consists of a casting of aluminium-metal or of a suitable aluminium-alloy, the latter being provided, at the surface of the part which

is subjected to the chemical and thermal **30** influences, with a protecting cover of copper preferably produced by electro-plating.

The invention is illustrated in the accompanying drawing in which Fig. 1 is a longitudinal section through the tuyère. Fig. 2 **35** is a view taken from the front side of the tuyère.

The aluminium-casting 1 contains the usual chamber 2 for the passage of the cooling-water. The protecting cover 3 of copper covers the nose of the tuyère up to the opening through which the blast-air escapes.

I am aware that prior to my invention tuyères for blast-pipes made of copper or of **45** aluminium have been used and I do not claim such a device broadly; but:

I claim:

50 A water cooled tuyère for blast pipes for high and other metallurgical furnaces formed of aluminium or aluminium alloy and having a protecting cover of copper covering the nose of the tuyère up to the outlet opening for the blast air.

In testimony whereof, I have signed my **55** name to this specification at Berlin, Germany, this 21st day of March, 1924.

THEODOR BERG.
